[57] CLAIM

The ornamental design for a powered lift for commode seat, as shown and described.

DESCRIPTION

FIG. 1 is a top, front perspective view of a powered lifter for commode seat showing our new design;

FIG. 2 is a front elevational view thereof;

FIG. 3 is a side elevational view taken from the right side of FIG. 2;

FIG. 4 is a side elevational view taken from the left side of FIG. 2;

FIG. 5 is a top plan view thereof.

The rear and bottom are open and conventional.

The toilet seat is shown in broken lines in FIGS. 2 and 5 for illustrative purposes only.
